W. A. IVES, OF NEW HAVEN, CONNECTICUT.

Letters Patent No. 90,755, dated June 1, 1869.

IMPROVEMENT IN AUGER-BITS.

The Schedule referred to in these Letters Patent and making part of the same.

To all whom it may concern:

Be it known that I, W. A. IVES, of New Haven, in the county of New Haven, and State of Connecticut, have invented a new Improvement in Auger-Bits; and I do hereby declare the following, when taken in connection with the accompanying drawings, and the letters of reference marked thereon, to be a full, clear, and exact description of the same, and which said drawings constitute part of this specification, and represent in—

Figure 1, a side view, and in

Figure 2, the cutting-end.

This invention relates to an improvement in double-twist auger-bits, the object being to combine in one instrument both a centre and auger-bit. To this end,

My invention consists in constructing one of the twists so as to terminate in a floor-lip, and the other in a spur-cutter, the screw being in the cutter between.

In order to the clear understanding of my invention, I will fully describe the same as illustrated in the accompanying drawings.

A represents a portion of an auger-bit, formed in the usual manner.

One of the twists terminates in a floor-lip, a, the

other in a spur-cutter, d, that twist being brought down so that the spur-cutter will stand perpendicular, or nearly so, as seen in fig. 3, and the cutter is formed by taking out or forming a recess, b, between the edge of the twist and the centre, as seen in fig. 1. Central between the two, a common screw-point is formed.

The advantages of this construction are—

First, that the floor-lip, which is but a termination of the twist upon which it is formed, may be easily filed or cut away to sharpen the cutter.

Secondly, the labor in its construction is less than either for a centre or auger-bit, and all the advantages of both are combined in one.

Having fully described my invention,

What I claim as new and useful, and desire to secure by Letters Patent, is—

In double-twist auger-bits, forming a floor-lip, a, upon one twist, and the other twist terminating in the spur-cutter d, and so as to form a recess between the said spur and the centre screw, substantially as specified.

W. A. IVES.
